L. R. BARBER.
INK FOUNTAIN DRIVE MECHANISM.
APPLICATION FILED JULY 5, 1921.

1,412,766.

Patented Apr. 11, 1922.

Fig. 1

UNITED STATES PATENT OFFICE.

LEWIS R. BARBER, OF FRESNO, CALIFORNIA, ASSIGNOR TO LISENBY MANUFACTURING COMPANY, OF FRESNO, CALIFORNIA.

INK-FOUNTAIN DRIVE MECHANISM.

1,412,766.

Specification of Letters Patent. Patented Apr. 11, 1922.

Application filed July 5, 1921. Serial No. 432,594.

To all whom it may concern:

Be it known that I, LEWIS R. BARBER, a citizen of the United States, residing at Fresno, county of Fresno, State of California, have invented certain new and useful Improvements in Ink-Fountain Drive Mechanism; and I do declare the following to be a full, clear, and exact description of the same, reference being had to the accompanying drawings, and to the characters of reference marked thereon, which form a part of this application.

This invention relates to improvements in printing presses, and particularly to a driving mechanism for the ink-fountain used to spread the ink onto the ink plate of the press, the present invention being more especially intended as an improvement over the type of fountain drive mechanisms shown in United States Patent No. 1,018,434, dated Feb. 27th, 1912, and United States Patent No. 1,192,455, dated July 25th, 1916.

The principal object of the invention is to devise a fountain driving mechanism which will be operated directly from the driving lever of the moving bed of the press, and so arranged that a great leverage is obtained, thereby reducing the power necessary to rotate the ink-fountain roll, which necessarily has a very tight fit with its trough.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Fig. 1 is a side outline of a press, showing my improved fountain-drive mechanism.

Fig. 2 is an enlarged side view, detached, of the fountain and the fountain-roll drive-lever.

Fig. 3 is a top plan view of the rear end of the press, showing the ink-fountain mechanism.

Fig. 4 is a fragmentary view showing the means of operating the fountain-drive lever from the moving-bed lever.

Referring now more particularly to the characters of reference on the drawings, the numeral 1 denotes the stand of the press, on

which is pivoted the stand-lever 2 for operating the moving-bed (not shown) and ink-plate 3, which is driven by means of a connecting rod 4 attached to a fly or gear-wheel 5, itself rotated by a motor or other suitable means (not shown).

Mounted on the stand or frame 1 at the rear end thereof is a pair of rigid arms 6, to which is secured the fountain structure frame 7, which carries a trough 8 in connection with which is turnably mounted the fountain roll 9, whose shaft 9^a carries a ratchet wheel 10 having a hub 11.

Turnably mounted on the hub 11 is a friction plate 12 connected by a link 13 to the ductor-roll bracket 14, pivoted on the frame 7, and which carries the ductor-roll 15.

Also independently and turnably mounted on the hub 11 is an arm or lever 16 which carries a friction member 17 adapted to yieldably engage the plate 12, and also carries a pawl 18 adapted to engage the wheel 10.

A link 19 connects the lever 16 with the main lever 20 which is pivoted on a bracket 21 secured to the stand 1, and is positioned substantially in transverse alignment with the stand-lever 2.

The lower end of the lever 20 is formed or provided with a grooved member 22 in which rides a roller 23 turnably mounted on a pin 24, which also forms the pivotal connection of the connecting rod with the lever 2.

In this manner, the connecting rod is used to drive two members—the levers 2 and 20, the rod only being directly connected to the one lever 2, the radial length of the other being different from that of the lever 2.

The pivotal connection of the link 19 with the lever 20 is intermediate the pivotal connection 20^a of the lever 20 with the bracket 21, and the driving connection of said lever with the roller 23.

If an ink fountain is also positioned at the front end of the press, as for two-color work, an additional link 25 is connected to the lever 20 the same distance above the pivotal connection 20^a as the link 19 connects with said lever below the pivotal connection, said link 25 extending to a pawl-lever 26, which operates the forward fountain member.

In operation, the reciprocation of the lever 2 imparts a like reciprocation to the lever 20, such movement being transmitted

through the link 19 to the pawl lever 16, the pawl on which alternately engages and disengages with the teeth of the ratchet wheel 10, intermittently rotating the roll 9.

5 At the same time, the movement of the lever 16 in the direction which rotates the ratchet wheel and ink roll, causes the friction member 17 to rotate the plate 12 somewhat, causing the ductor roll 15 to be then 10 pressed firmly against the roll 9, to receive ink therefrom, while the reverse movement of the pawl lever draws said ductor roll away from the ink roll and presses it against the ink plate 3, thus inking the same.

15 The roll 9 has a very tight fit in the trough 8, so as to prevent leakage of thin ink, and considerable power is therefore necessary to rotate the roll. For this reason, I have employed the leverage system herein shown and 20 described, and which operates successfully and efficiently, the multiplication of the leverage obtained, first at the lever 20 and then at the lever 16, not only absorbing but little power from the motor or other driving 25 means employed, but allowing me to use comparatively light parts with but little chance of breakage.

From the foregoing description it will be readily seen that I have produced such a 30 device as substantially fulfills the objects of the invention as set forth herein.

While this specification sets forth in detail the present and preferred construction of the device, still in practice such deviations 35 from such detail may be resorted to as do not form a departure from the spirit of the invention, as defined by the appended claims.

Having thus described my invention, what I claim as new and useful and desire to secure by Letters Patent, is:—

40 1. An ink-fountain drive mechanism for printing presses comprising with a fountain ink-roll, and a reciprocating connecting rod of the press, a ratchet wheel on the roll, a 45 pawl-lever mounted in connection with the

roll and carrying a pawl adapted to engage the ratchet wheel, a lever pivotally mounted on the press stand and adapted to be reciprocated by the connecting rod, and a link connecting said levers.

50 2. An ink-fountain drive mechanism for printing presses comprising with a fountain ink-roll, and a reciprocating connecting rod of the press, a ratchet wheel on the roll, a pawl-lever turnably mounted concentric with 55 the roll and carrying a pawl adapted to engage the ratchet wheel, a lever pivotally mounted on the press stand, a link connecting said levers, said last named lever having a grooved portion, and a projection from 60 the connecting rod riding in the groove.

3. An ink-fountain drive mechanism for printing presses comprising with a fountain ink-roll and a reciprocating connection rod of the press, a ratchet wheel on the roll, a 65 pawl-lever turnably mounted on the roll-shaft and carrying a pawl adapted to engage the ratchet-wheel, a lever pivotally mounted on the press-stand, a link connecting said levers, and a driving member projecting from the connecting rod and flexibly 70 engaging the last named lever to reciprocate the same.

4. An ink-fountain drive mechanism for 75 printing presses comprising with a fountain ink-roll, a stand-lever for operating the moving-bed of the press and a reciprocating connecting rod connected to said stand-lever, a lever mounted in connection with the ink-roll, means between said roll and lever 80 for intermittently rotating said roll with a reciprocatory movement of said lever, a fountain-drive lever pivotally mounted on the press stand, a link connecting said last named levers, and a driving member projecting from the connecting rod at its point 85 of connection with the stand lever and flexibly engaging the fountain-drive lever.

In testimony whereof I affix my signature
LEWIS R. BARBER.
